SPRING RACK

Arthur Faber, 17668 Adrian, Southfield, Mich.

Filed Oct. 3, 1962, Ser. No. 71,984

Term of patent 14 years

(Cl. D80—9)

FIGURE 1 is a front perspective view of a spring rack showing my new design, the rear being substantially plain; FIGURE 2 is a top view thereof; and

FIGURE 3 is an elevational view taken from one end thereof, the opposite end being a mirror image of the end shown.

I claim:

The ornamental design for a spring rack, as shown and described.
